UNITED STATES PATENT OFFICE

162,749

COMB

Frank Polimeni, Steubenville, Ohio

Application September 22, 1948, Serial No. 148,715

Term of patent 7 years

(Cl. D86—8)

To all whom it may concern:

Be it known that I, Frank Polimeni, a citizen of no country, formerly a citizen of Italy, residing at Steubenville, in the county of Jefferson, and State of Ohio, have invented a new, original, and ornamental Design for a Comb, of which the following is a specification, reference being had to the accompanying drawing, forming part thereof.

I claim:

The ornamental design for a comb as shown.

FRANK POLIMENI.
